DESIGN FOR A SUGAR BOWL TOP

William A. Hart, Chicago, Ill., assignor to The Sanitary Sugar Bowl Company, Pittsburgh, Pa., a co-partnership composed of Harry H. Gahagen and Charles F. Gahagen

Application January 25, 1938, Serial No. 74,518

Term of patent 14 years

To all whom it may concern:

Be it known that I, William A. Hart, a citizen of the United States, residing at Chicago, in the county of Cook, and State of Illinois, have invented a new, original, and ornamental Design for Sugar Bowl Tops, of which the following is a specification, reference being had to the accompanying drawing, forming part thereof.

In the drawing Fig. 1 is a top plan view of the sugar bowl top, showing my new design; Fig. 2 is a side elevational view thereof; and Fig. 3 is a cross-sectional view taken on line III—III of Fig. 1.

I claim:

The ornamental design for a sugar bowl top, as shown.

WILLIAM A. HART.
